UNITED STATES PATENT OFFICE.

OSKAR BRIX, OF LEIPSIC-GOHLIS, GERMANY.

ROPE-GRIP FOR SUSPENDED ROPE RAILWAYS.

No. 829,056.

Specification of Letters Patent.

Patented Aug. 21, 1906.

Application filed April 22, 1904. Serial No. 204,348.

To all whom it may concern:

Be it known that I, OSKAR BRIX, a subject of the German Emperor, residing at 10 Aeussere Halleschestrassse, Leipsic-Gohlis, in the Empire of Germany, have invented certain new and useful Improvements in Rope-Grips for Suspended Rope Railways; and I do hereby declare the following to be a full, clear, and exact description of the invention, such as will enable others skilled in the art to which it appertains to make and use the same.

This invention relates to a rope-grip for suspended rope railways in which a worm-spindle is employed in the usual manner for clamping the gripping-jaws together and the weight of the vehicle acts so as to operate the gripping-jaws; and it consists in suspending the vehicle from a lever fixed on the worm-spindle and tending to close the jaws on the hauling-rope.

In the accompanying drawings, Figure 1 is a side elevation, and Fig. 2 a transverse section, of the rope-grip.

In carrying out the invention the arm of a pivoted gripping-jaw *b*, which co-operates with a fixed jaw *a*, carries a toothed segment *b'*, which gears with the worm-spindle *g*, mounted to rotate in a trolley-frame *d*. On the worm-spindle a lever *h* is firmly keyed, and to this lever the hanging support or yoke *k*, which carries the vehicle, is pivotally suspended in such a manner that the weight of the vehicle tends constantly to turn the lever *h* downward, and thereby secures the pivoted clamping-jaw *b* in the clamping position.

The lever *h* is provided at its free end with a roller *p*, which when the vehicle is to be released from the hauling-rope runs onto a rail in the known manner.

What I claim, and desire to secure by Letters Patent, is—

1. In a friction-grip, the combination with a traveling frame and rollers and a rope-clamp supported thereby, of an actuating screw-spindle for the rope-clamp and means for actuating the said spindle and to which the load is directly connected for support. 45

2. In a friction-grip, the combination with a traveling frame and rollers and a rope-clamp supported thereby, of an actuating screw-spindle for the rope-clamp, a crank connected to the screw-spindle, and an arm pivotally hung from the crank and to which the load is directly connected for support. 50

3. In a friction-grip, the combination with a frame and rollers mounted therein, of a crank-arm, a screw-spindle actuated thereby, a gripping-jaw secured to the screw-spindle, a fixed jaw, a hanger to which the load is attached, and a direct connection between the crank-arm and the hanger. 55

4. In a rope-grip for suspended railways, a fixed clamping-jaw, a pivoted gripping-jaw coöperating with the fixed jaw to grip the rope, an arm or lever on the gripping-jaw terminating in a toothed segment, a worm-spindle gearing with said segment, a lever-arm keyed on the worm-spindle, and supporting the vehicle in such a manner that the weight thereof tends to turn the worm-spindle which acting on the toothed lever causes the jaws to exert a uniform pressure on the rope both when traveling on inclines and on the level. 70

In testimony whereof I have affixed my signature in presence of two witnesses.

OSKAR BRIX.
